(57) **CLAIM**

The ornamental design for a light fixture, as shown and described.

DESCRIPTION

FIG. 1 is a perspective view from below of the light fixture, a support arm and light-engine details being shown in phantom lines;

FIG. 2 is a perspective view from above of the light fixture of FIG. 1, heat-sink fins being shown in phantom lines;
FIG. 3 is a bottom plan view of the light fixture of FIG. 1;
FIG. 4 is a top plan view of the light fixture of FIG. 1;
FIG. 5 is a right-side elevation of the light fixture of FIG. 1;
FIG. 6 is a left-side elevation of the light fixture of FIG. 1;
FIG. 7 is a front elevation of the light fixture of FIG. 1; and,
FIG. 8 is a rear elevation of the light fixture of FIG. 1.
The phantom lines are provided for illustrative purposes only and form no part of the claimed design.

1 Claim, 6 Drawing Sheets
